United States Patent Office

Des. 227,911
Patented July 24, 1973

227,911

POULTRY HOUSE

Gerald L. Kitson, 9709 Belding Road,
Rockford, Mich. 49341

Filed May 17, 1971, Ser. No. 144,374

Term of patent 14 years

Int. Cl. D30—02

U.S. Cl. D30—1

FIG. 1

FIG. 2

FIG. 3

FIG. 4

FIG. 1 is a fragmentary side, top and end perspective view of a poultry house, showing my new design with a portion of the roof broken away and omitted to show the interior, and another portion broken away and omitted to indicate indeterminate length;

FIG. 2 is an opposite end elevational view to a reduced scale;

FIG. 3 is a fragmentary side elevational view to a reduced scale, a portion being broken away and omitted to show the interior and to indicate indeterminate length; and

FIG. 4 is a fragmentary top plan view thereof to a reduced scale, a portion being broken away and omitted to show the interior and to indicate indeterminate length.

I claim:

The ornamental design for a poultry house, as shown and described.
